UNITED STATES PATENT OFFICE.

VIRGIL OLDBERG, OF DETROIT, MICHIGAN, ASSIGNOR TO OLDBERG MANUFACTURING COMPANY, OF DETROIT, MICHIGAN, A CORPORATION OF MICHIGAN.

MUFFLER.

Application filed May 23, 1921, Serial No. 471,633. Renewed March 10, 1924.

To all whom it may concern:

Be it known that I, VIRGIL OLDBERG, a citizen of the United States, and residing at Detroit, in the county of Wayne and State 5 of Michigan, have invented a new and Improved Muffler, of which the following is a specification.

This invention relates to means for deadening the sounds of gases which move at 10 irregular speeds, and while especially adapted for reducing the noises of the exhausts of internal combustion engines, these mufflers may be employed wherever else gases are drawn in or expelled at intervals or at 15 varying rates. The object of this invention is to provide a muffler which will cause the least amount of back-pressure and will reduce the sound of the moving gases within 20 the muffler and at the same time eliminate the drumming noises so often noticed in connection with mufflers for exhaust gases.

This invention consists of a plurality of shells, one within the other, and heads to 25 position the shells so that each will be eccentric relative to the next adjacent shell, the inner shell and the heads being perforated to permit the passage of gas, and a diaphragm intermediate the ends of the inner shell to prevent the direct passage of gases 30 the whole length thereof.

It further consists of the details of construction illustrated in the accompanying drawing and particularly pointed out in the claims.

35 In the accompanying drawing, Fig. 1 is a central longitudinal section of this improved muffler. Fig. 2 is an end view thereof. Fig. 3 is a transverse section on the line 3—3 of Fig. 1. Fig. 4 is a fragmentary section of a shell.

Similar reference characters refer to like parts throughout the several views.

The muffler shown in the drawing consists of the two heads 1 and 2, one provided with 45 an inlet pipe 3 and the other with a discharge pipe 4, an outer shell 5 which is preferably corrugated, thimbles 6 and 7 within the ends thereof, an intermediate shell 8 mounted on the thimbles, a diaphragm 9 mounted within the intermediate shell to 50 divide it into two sections, and a two-part inner shell 10—11 mounted on the thimbles 6 and 7 and on the diaphragm 9.

The heads 1 and 2 are preferably formed

with the circumferential flanges 13 adapted 55 to be welded to the ends of the outer shell 5, with stiffening ribs 14, and with inner flanges 16 adapted to be welded to the inlet pipe 3 and discharge pipe 4. The thimbles 6 and 7 are each preferably formed with circumferential flanges 17 adapted to be welded to the outer shell 5 and two cylindrical portions 18 and 19 eccentric to each other. The intermediate shell 8 is mounted on the outer cylindrical portions 18 and has two groups 60 65 of perforations 20 and 21 opposite each other.

The diaphragm 9 has a circumferential flange 23 adapted to be welded to the intermediate shell 8 and a cylindrical portion 24 70 eccentric thereto to which the adjacent ends of the two parts 10 and 11 of the inner shell may be attached. These two parts also have perforations 25 and 26 opposite each other.

Gases entering through the pipe 3 will 75 flow along the inner shell 10 and pass out through the openings 25, then flow around this inner shell, expanding as they reach the greater space between it and the intermediate shell 8 and then pass through the 80 holes 20 into the space within the outer shell. The gases then move spirally around the intermediate shell to the holes 21 in the intermediate shell and again enter at the opposite side of the diaphragm 9. After 85 again passing half way around the inner shell, the gases enter through the holes 26 and then flow longitudinally to the discharge pipe 4 which may be of any desired shape and length.

90 In order that the gases may flow through the openings 20, 21, 25 and 26 as freely as possible, the metal around these holes should be drawn to thimble form, as indicated in Fig. 4, the small rings 27 being on those 95 sides of the shells toward which the gases flow through these openings and the entrances of these openings having rounded edges.

The outer shell usually remains at much 100 more even temperature than the intermediate and inner shells and when corrugated as shown permits these shells to expand and contract without causing the joints between the shells and thimbles to break. The diaphragm 9 not only causes the gases to take a round-about course, but it reduces the vibration of the inner and intermediate shells 105

which almost entirely eliminates the drumming sound so frequently heard in mufflers. The corrugated outer shell still further cuts down this noise, and, because of its great area, serves to cool the gases and thus reduces their volume and the back pressure. It will be noted that in each case, the space between the shells is narrower at the point of entry of the gas and increases in a predetermined degree to the point of discharge.

10 The details of this construction and the proportions of the parts may all be changed by those skilled in the art without departing from the spirit of my invention as set forth 15 in the following claims.

I claim:—

1. In a muffler, the combination of a series of cylindrical shells mounted within each other, heads closing the ends of the outer shell, thimbles within the ends of the outer shell and each having cylindrical extensions intermediate and inner shells mounted on said extensions, the inner shell being concentric with the outer shell and the intermediate shell being eccentric to the other two, said inner shell being in two sections, and a diaphragm mounted in the intermediate shell and having a cylindrical projection fitting the adjacent ends of the two sections of the inner shell, said inner and intermediate shells being formed with holes to permit the passage of exhaust gases, the holes in each of the inner shells being along longitudinal lines substantially diametrically opposite each other at opposite sides of the diaphragm.

2. In a muffler, the combination of a series of cylindrical shells within each other, heads closing the ends of the outer shell, and sheet metal thimbles within the ends of the outer shell and formed with inwardly extending cylindrical extensions to receive said inner shells, the inner extensions being respectively eccentric to and projecting beyond the next outer extensions, said inner shells having holes to permit the passage of gases.

3. In a muffler, the combination of a plurality of cylindrical outer and inner shells

eccentrically mounted within each other, means closing the ends of the outer shell, a diaphragm mounted between the ends of the inner shell, and inlet and discharge passages connected with the ends of the outer shell, the inner shell being formed with lines of holes to permit the passage of gases, said lines being substantially diametrically opposite each other at opposite sides of the diaphragm and along the plane passing through the axes of the shells, those portions of the inner shell diametrically opposite the lines of holes being imperforate.

4. In a muffler, the combination of a series of cylindrical shells eccentrically mounted within each other with their axes in substantially the same plane, means closing the ends of all but the inner shell, a diaphragm mounted within and between the ends of all but the outer shell, and inlet and discharge passages connected with the ends of the outer shell, the inner shells being formed with lines of holes to permit the passage of gases, said lines being substantially diametrically opposite each other in each shell at opposite sides of the diaphragm therein, one of the lines of holes of each shell opening into the narrowest and the other into the widest portion of the space surrounding it, those portions of the inner shell diametrically opposite the lines of holes being imperforate.

5. In a muffler, the combination of inner and outer shells, the central line of the inner shell being at one side of the central line of the outer shell, and a diaphragm mounted within the inner shell between its ends, said inner shell being formed with lines of holes substantially diametrically opposite each other at opposite sides of the diaphragm, the holes on one side of the diaphragm opening into the space between the shells where it is narrowest and the other row of holes where such space is widest, those portions of the inner shell diametrically opposite the lines of holes being imperforate.

VIRGIL OLDBERG.
